AMPLIFIER

Robert B. Dome, Schenectady, N. Y., assignor to
General Electric Company, a corporation of
New York

Application March 1, 1933. Serial No. 659,199

4 Claims. (Cl. 179—171)

My invention relates to amplifiers and more particularly to impedance- or resistance-capacitance coupled amplifiers for use over a wide range of audible and super-audible frequencies. 5 In transmitters and receivers such as are used for television purposes, it is necessary to provide an amplifier having a substantially flat amplification characteristic for amplifying the frequency impulses which produce the television image. Such frequency impulses may range from an audio frequency of 20 cycles to a super-audible frequency of 250,000 cycles or more. It has been found that the ordinary resistance-capacitance coupled amplifier amplifies both audible 10 and super-audible frequencies, and this amplifier would be suitable for this purpose except for the fact that the amplification characteristic begins to droop appreciably in the neighborhood of 20,000 cycles and this drooping becomes more prominent as the frequency increases. To obtain the proper amplification of the higher frequencies which extend well into the radio frequency range, several stages of amplification would be necessary and the lower frequencies would tend to overload 15 the amplifier. This drooping characteristic is largely due to the inter-electrode capacities present within the electron discharge amplifying device.

In accordance with my invention, I provide a 20 resistance-capacitance coupled amplifier with means for neutralizing the effects of the grid-to-anode capacity, particularly at the higher frequencies at which the amplifier is operated. This arrangement prevents the amplification 25 characteristic from drooping, due to the elimination of the effect of the inter-electrode capacities of the electron discharge device.

My invention has for one of its objects to provide a resistance-capacitance coupled amplifier 40 with means for neutralizing the grid-to-anode capacity at the higher frequencies.

A further object of my invention is to provide a resistance-capacitance coupled amplifier with an arrangement for maintaining the grid-to-anode impedance at a high value for the 45 low frequencies and increasing this impedance as the frequency increases throughout the operating range of the amplifier.

The novel features which I believe to be characteristic of my invention are set forth in the appended claims. My invention itself, however, both as to its organization and method of operation, together with other objects and advantages thereof, will be better understood by referring to the following description taken in con-

nection with the accompanying drawing in which Fig. 1 illustrates one form of the invention; Fig. 2 illustrates a preferred embodiment of my invention, and Fig. 3 illustrates the operating characteristic of my invention.

Referring to Fig. 1 of the drawing, I have illustrated therein an amplifier of the resistance-capacitance coupled type in which the grid, or control element, of the electron discharge device 1 is coupled to a source of oscillations having frequencies extending over a range including both low audible frequencies and relatively high radio frequencies. This source may for example comprise a television machine, or one of the earlier stages of an amplifier for television currents. The control element may be biased negatively by a source of potential 2 connected to the cathode and the normal grid coupling resistor 3. Anode current is supplied to the electron discharge device 1 from a source of potential 4 through the anode coupling resistor 5. The anode coupling capacitor 6 permits the amplifier to be coupled to a succeeding similar stage of amplification as shown or any suitable utilization device. The amplifier just described constitutes the usual form of an impedance- or resistance-capacitance coupled amplifier. A source of oscillations 7 is connected to the input circuit by connections to the grid and the cathode of the discharge device 1.

In accordance with my invention, an inductor 8 is connected in the input circuit between the grid coupling resistor 3 and the grid or control element of the electron discharge device 1. This inductor 8 is so constructed and arranged that at low frequencies it has substantially no impedance, but at the higher frequencies and throughout the remainder of the operating range of the amplifier it increases in impedance with the increase in frequency of the oscillations to be amplified. A second inductor 9 is inductively coupled to the inductor 8 and in this particular embodiment is connected at one extremity to the inductor 8. The inductors 8 and 9 may be sections of a continuous inductor as disclosed in Fig. 1, with the midpoint connected to the grid coupling resistor 3. The other extremity of the inductor or inductor section 9 is connected through a variable capacitor 10 to the cathode of the electron discharge device. The capacity of this capacitor is normally adjusted to a value equal to the normal grid-to-cathode capacity of the electron discharge device 1. A neutralizing or balancing capacitor 11 is connected between the anode of the discharge device and a point between the

capacitor 10 and the inductor 9. The capacitor 11 is adjusted to a value equivalent to the normal grid-to-anode capacity of the electron discharge device. The inductors 8 and 9, as now arranged, each has the same capacity value across it, as the inductor 8 has across it the grid-to-cathode capacity of the discharge device while the inductor 9 has across it the capacitor 10 which is adjusted to the same capacity value as the grid-to-cathode capacity.

The operation of this amplifier at the lower frequencies is that of the ordinary resistance-capacitance coupled amplifier, as any voltage impressed across the input circuit does not produce any appreciable drop across the inductor 8. However, as the amplifier operates at the higher frequencies, a portion of the voltage produced by the amplifying action of device 1 across anode resistor 5 is coupled back through the capacitor 11 to produce magnetic flux in the inductor 9. The flux of inductor 9 links with inductor 8 so that a potential is induced therein which is applied to the grid of the discharge device 1. The voltage impressed upon this grid increases with the frequency of the amplified currents and is opposite in phase to the voltage impressed thereon by the coupling of the output voltage across the resistors through the grid-to-anode capacity of the discharge device. At the highest frequencies amplified, the voltage impressed upon the grid is equal to the voltage impressed thereon due to the grid-to-anode capacity. The impedance from grid to cathode in this arrangement may be expressed by the following equation:

$$35 \quad Z = \sqrt{R_1^2 + W^2 L^2}$$

where R_1 is the resistance of the coupling resistor 3, L is the inductance of the inductor 8 and W is equal to $2\pi F$, where F is equal to the frequency. It is therefore apparent from this equation that as the higher frequency ranges are approached by the amplifier the inductive reactance of L becomes appreciable so that the impedance Z will increase with the frequency.

45 Referring to Fig. 2, I have shown therein an amplifier of the resistance-capacitance coupled type which is similar to that shown in Fig. 1. Like parts in Fig. 2 are given the same reference numerals as in Fig. 1. It will be noted, however, that the inductors 8 and 9 in Fig. 2 are separate and distinct and that the upper extremity of the inductor 9 is now connected at a point between the coupling resistor 3 and the grid biasing potential 2, thus avoiding losses through the resistor 3, and that the side of the capacitor 10 which formerly was connected directly to the cathode is now connected to this same point between the resistor and biasing source of potential. This arrangement has the advantage that the effect of neutralization of grid-to-anode capacity becomes effective at lower frequencies than in the circuit in Fig. 1 while still maintaining the same value of inductors and coupling resistors. Thus in this arrangement the voltage drop across 55 8 is appreciable at a somewhat lower frequency since none of the voltage present across resistor 5 which is coupled through capacitor 11 to the inductor 9 is impressed upon the resistor 3. This improved resistance-capacitance coupled amplifier, therefore, permits a higher voltage to be induced in the inductor 8 at the lower frequencies, and at the same time allows the same degree of neutralization to be maintained at high frequencies where the induced voltage is equal to

the voltage produced by the inter-electrode capacity.

In Fig. 3, I have shown at AB the normal amplification characteristic of a resistance-capacitance coupled amplifier which begins to droop appreciably in the neighborhood of 20,000 cycles. The curve shows amplification in decibels plotted against frequency with the line X at the highest frequency to be amplified. The improvement in the characteristic due to the use of an inductor 8 in the input circuit is shown in curve AC, and this is primarily due to the fact that the inductor tends to maintain constant the impedance of the input circuit. The curve AD shows the improvement obtained by the neutralization of the grid-to-anode capacity. Curve AE shows the amplification characteristic of an amplifier such as shown in Fig. 2 wherein the inductors 8 and 9 and associated circuits cooperate to maintain the amplification constant over the entire frequency range to the highest frequency to be amplified.

The embodiments of the invention illustrated and described herein have been selected for the purpose of clearly setting forth the principles involved. It will, of course, be understood that I do not wish to be limited thereto, since it is apparent that the principles herein disclosed are susceptible of numerous other applications, and modifications may be made in the circuit arrangements and in the instrumentalities employed without departing from the spirit and scope of my invention as set forth in the appended claims.

What I claim as new and desire to secure by Letters Patent of the United States is:

1. The combination, in an impedance-capacitance coupled amplifier, of an electron discharge device having a cathode, an anode and a grid element, an input circuit for said device including a coupling impedance connected to said cathode and said grid element, a source of oscillations connected to said input circuit for amplification, said oscillations extending over a frequency range from low audio frequencies to relatively high radio frequencies, an output circuit for said device including a coupling impedance connected between said cathode and anode, an inductor connected in said input circuit between said grid and said coupling impedance, said inductor having substantially no impedance at audio frequencies and having increasing impedance with increasing frequency in the higher frequency position of the operating frequency range, and means connected to said anode and said input circuit including an inductor arranged in inductive relation to said first inductor for impressing upon said grid a voltage increasing in value with the increasing frequency of the amplified currents and opposite in phase to the voltage impressed upon said grid through the inherent capacity between said anode and said grid element.

2. The combination in a resistance-capacitance coupled amplifier comprising an electron discharge device having an anode, a cathode and a grid, an input circuit including a coupling resistor connected between said cathode and grid, an output circuit including a coupling resistor connected between said cathode and anode and a coupling capacitor connected to said anode, a source of oscillations connected to said input circuit for amplification, said oscillations having frequencies extending over a frequency range from low audio frequencies to relatively high

- radio frequencies, said amplifier having an amplification characteristic which is drooping in the higher frequency range, of means connected in said input circuit for increasing the input impedance thereof with the increasing frequency in said higher frequency range, and means connected between said input circuit and said anode for impressing upon said grid a voltage increasing in value with the increasing frequency of 5 the higher frequencies of the oscillations and opposite in phase to the voltage impressed upon said grid through the inherent capacity between said anode and said grid whereby said means cooperate to prevent said amplification characteristic from drooping. 10
3. The combination, in a resistance-capacitance coupled amplifier comprising an electron discharge device having an anode, a cathode and a grid, an input circuit including a coupling resistor connected between said cathode and grid, an output circuit including a coupling resistor connected between said cathode and anode and a coupling capacitor connected to said anode, a source of oscillations connected to said input circuit for amplification, said oscillations having frequencies extending over a frequency range including both low audible frequencies and relatively high radio frequencies, an output circuit comprising a coupling resistor connected between said cathode and said anode and a coupling capacitor connected to said anode, a second inductor arranged in inductive relation to said first inductor and connected in series with a capacitor having a value equal to the inherent grid-to-anode capacity, said latter capacitor and said second inductor being connected between said cathode and said anode, and a capacitor having a value equal to the cathode-to-grid capacity connected across said second inductor, said inductors and capacitors cooperating to prevent the amplification characteristic from drooping. 15 20 25 30 35
4. In a resistance-capacitance coupled amplifier normally having a drooping amplification characteristic, an electron discharge device having a cathode, an anode and a grid, an input circuit comprising a grid coupling resistor connected to said cathode and an inductor connected between said resistor and said grid, a source of oscillations connected to said input circuit for amplification, said oscillations having frequencies extending over a frequency range including both low audible frequencies and relatively high radio frequencies, an output circuit comprising a coupling resistor connected between said cathode and said anode and a coupling capacitor connected to said anode, a second inductor arranged in inductive relation to said first inductor and connected in series with a capacitor having a value equal to the inherent grid-to-anode capacity, said latter capacitor and said second inductor being connected between said cathode and said anode, and a capacitor having a value equal to the cathode-to-grid capacity connected across said second inductor, said inductors and capacitors cooperating to prevent the amplification characteristic from drooping. 40 45 50 55 60 65 70 75 80 85 90 95 100 105 110
